UNITED STATES PATENT OFFICE.

SAMUEL L. FRENCH AND RICHARD B. MELLON, OF LIGONIER, PA.

SPARK-ARRESTER.

SPECIFICATION forming part of Letters Patent No. 245,621, dated August 16, 1881.

Application filed May 25, 1881. (No model.)

To all whom it may concern:

Be it known that we, SAMUEL L. FRENCH and RICHARD B. MELLON, citizens of the United States of America, residing at Ligonier, in the 5 county of Westmoreland and State of Pennsylvania, have invented certain new and useful Improvements in Spark-Arresters; and we do hereby declare the following to be a full, clear, and exact description of the invention, such 10 as will enable others skilled in the art to which it appertains to make and use the same, reference being had to the accompanying drawings, and to letters or figures of reference marked thereon, which form a part of this specification. 15

Figure 1 is a side view of the front portion of a locomotive, showing a central sectional view of our improved spark-arrester. Fig. 2 is a perspective view thereof, and Fig. 3 is a 20 detail view of the same.

This invention has relation to improvements in spark-arresters attached to the chimney of locomotives or portable engines; and its object is to prevent the escape of the sparks from the 25 engine-fire to the open air, and providing a means of collecting and conducting them to a receptacle on the front of the locomotive or engine.

Our improvement, therefore, consists in perforating the funnel of the smoke-stack and attaching to the outside a funnel-shaped receptacle, with the smoke-stack enveloped by and extending through the side of the funnel, so as to throw the escape entirely outside and to 35 the front of the stack.

Our improvement further consists in the novel arrangement and combination of the parts, as will be hereinafter more specifically set forth and claimed.

The letter A represents the chimney, of the 40 usual construction, formed with the extending sleeve B, running inside and beyond the junction of the chimney with the swell of the stack. On the tongue of this sleeve are fixed rigidly the standards a, to which is secured the cone C, suspended with the apex down and over the 45 center of the aperture of the chimney. The object of this cone is to deflect the cinders or sparks as they emerge from the chimney against

the wire screen, from whence they are thrown 50 to the perforated funnel D. The funnel D is secured in the swell of the stack, and must be raised above the floor of the funnel, to which it is fastened at the top edges. It is supplied with two or more large holes, in addition to the 55 regular perforations, for the purpose of permitting the egress of larger cinders which may be thrown up from the pipe.

The letter E represents the funnel attached 60 to the outside of the lower section of the swell of the chimney, and formed so that the chimney passes through one side of the funnel, and is surrounded or enveloped by the metal of the funnel, and the escape thrown clear of the chimney and in front of it, substantially as 65 seen in the drawings. (See Fig. 1.)

The letter F shows a metallic conducting pipe 70 secured to the small end of the funnel E, and from thence extending to and opening into the top of the ash or cinder box G, which is mounted 75 on a platform fixed in front of the stack or boiler, and provided with hopper-shaped bottom and sliding or hinged discharge door H, through which the refuse can be dropped out. This cinder-box is made of sufficient size to 75 meet the requirements of the engine or the length of the trip to be run.

This improvement may be attached to the common chimney of a locomotive by connecting or riveting the funnel E to the swell of the 80 chimney, and forcing the extending sleeve B, with the deflector, to the top of the pipe, the other parts being arranged as before described.

It will be observed that the course of operation will be as follows: As the draft throws up the 85 sparks and cinders they strike the deflector, and from thence pass to the screen of the chimney, and are thrown downward in the perforated funnel, through which they pass to the basin of the funnel E, and thence down the pipe into 90 the box, and may be withdrawn from there at pleasure.

It is obvious that slight changes may be made in the construction of the parts and the arrangement of the same without departing 95 from the spirit of our invention.

What we claim as our invention, and desire to secure by Letters Patent, is—

1. The combination, with a smoke-stack, of
an irregular-shaped funnel, E, attached to and
surrounding the smoke-stack, and provided
with a perforated diaphragm, D, arranged sub-
stantially as described.

2. The combination, substantially as de-
scribed, of the smoke-stack, with the funnel E
surrounding the same, and provided with a per-
forated diaphragm, D, the connecting-pipe, and
a chest or deposit-box, substantially as described.

In testimony whereof we affix our signatures
in presence of two witnesses.

SAMUEL L. FRENCH.
RICHARD B. MELLON.
